UNITED STATES PATENT OFFICE.

CLARENCE L. DEWEY, OF ELKHART, INDIANA, ASSIGNOR TO OUTING MANUFACTURING CO., A CORPORATION OF INDIANA.

STRINGED MUSICAL INSTRUMENT.

Application filed December 10, 1926. Serial No. 153,752.

This invention relates to musical instruments, and more particularly to a string instrument of the ukulele or banjo type or that type of musical instrument requiring a stretched skinhead such as a snare drum or the like. The invention pertains more directly to improved instrument top members and retaining rings adapted to interfit with one another to permit heads to be secured in position when dry without necessitating previous forming thereof on special fixtures when the heads are wet as has been the custom heretofore.

It is an object of this invention to provide an instrument of the skinhead type having an improved top member and ring so constructed that a skinhead may be stretched into position dry without previous forming.

It is also an object of this invention to provide a musical instrument having a grooved top member adapted to be securely pressed into position upon an instrument body with said top provided with nuts rigidly secured in position at spaced intervals for the purpose of receiving adjustable screws which serve to hold a retaining ring in position interfitting said top member in such a way that a skinhead may be stretched into position when dry by adjusting the retaining ring by means of said screws.

It is furthermore an object of this invention to provide a musical instrument such as a ukulele, a banjo, or a drum with interfitting ring members adapted to be adjusted with respect to one another to permit a head to be stretched across the opening in one of said ring members when the head is dry with said head resting on the crown of an annular bead forming a part of the other of said ring members.

It is an important object of this invention to provide a musical instrument of the ukulele or banjo type with interfitting top ring members provided with adjustable screws and nuts so arranged that a skinhead may be stretched into position when dry and the slack in said head taken up by the adjustment of said screws after the skinhead has been in use or when the same needs stretching.

Other and further important objects of this invention will be apparent from the disclosures in the specification and the accompanying drawings.

This invention (in a preferred form) is 55 illustrated in the drawings and hereinafter more fully described.

On the drawings:

Figure 1 is a top plan view of a string instrument embodying the principles of this 60 invention.

Figure 2 is a fragmentary bottom plan view thereof.

Figure 3 is an enlarged longitudinal section of the instrument taken on the line 65 III-III of Figure 1.

Figure 4 is an enlarged fragmentary detail section taken on line IV-IV of Figure 1.

Figure 5 is a top plan view of a modified 70 form of string instrument embodying the principles of this invention.

Figure 6 is an enlarged transverse section of the instrument taken on line VI-VI of Figure 5, with parts omitted.

Figure 7 is a reduced section taken on line 75 VII-VII of Figure 6.

Figure 8 is a fragmentary detail section of the top member illustrating the key hole slots for receiving the strings.

As shown on the drawings:

The reference numeral 1 indicates the bottom of a one piece instrument constructed of sheet metal and pressed into form to afford a flange or wall 2. The bottom of the body section or casing is provided with a pair of F slots or tone holes 3. Rigidly secured to the casing rim or side wall 2 by means of a block 4 and retaining screws 5 is a neck 6 constructed of wood and having the 90 outer end shaped to form a peg head 7. Mounted on the peg head 7 are a plurality of pegs 8 to which the upper ends of strings 9 are secured. The strings 9 are conducted downwardly over the upper face of the neck 6 above the frets 10 which are mounted transversely of the finger board surface of said neck 6. The strings 9 are also conducted over a bridge 11 with the lower ends of said strings engaged in the reduced ends of key hole slots 12.

The key hole slots 12, in the instrument illustrated are provided in the upper face of a flanged outer annular ring 13 forming part of a pressed metal top member. The top member is constructed of sheet metal pressed into form to afford an outer flange or rim 14 integrally formed on the outer periphery of

said ring portion 13. Integral with the inner periphery of the ring portion 13 is a channel 15, the inner peripheral flange of which is directed upwardly and has the upper margin thereof deflected inwardly at an angle to form a beveled flange 16 forming a ridge or crown 17 at the right portion. Struck inwardly from the flat ring portion of the channel section 15 of the top member 10 are a plurality of spaced tongues or lugs 18. Riveted or otherwise rigidly secured at intervals to the bottom surface of the flat ring portion of the channel section 15 of the top member are a plurality of nuts 19.

15 A skinhead retaining or stretching ring 20 of channel cross section is provided to coact with the top member and is formed with a plurality of spaced openings to receive retaining screws 21 which project downwardly 20 through the channel ring 15 of the top member and have threaded engagement with the nuts 19. With the improved top member and retaining ring just described it is possible to accomplish a function heretofore impossible in the art of producing skinhead musical instruments. With the improved top member and retaining ring it is possible to stretch a skinhead 22 in position while dry without previous forming on special fixtures which first require wetting of the skinheads. The improved instrument is thus constructed to obviate wetting of skinheads, making it possible to apply a skinhead 22 across the crown or annular ridge 17 of the 25 top member with the peripheral margin of the skinhead provided with a plurality of spaced short radial slots 23 (Figure 4) to permit the retaining screws 21 projecting downwardly through the casing ring 20 to 30 project through the skinhead slots 23 to permit engagement with the nuts 19. The outer margin of the skinhead projects into the channel portion 15 of the top member and is adapted to be engaged by the inner peripheral flange of the retaining ring 20 so that when the screws 21 are threaded downwardly through the nuts 19 the retaining ring will cause the skinhead to be stretched into position with the inner peripheral flange of the retaining ring acting to force portions of the skinhead margin downwardly between the inner peripheral flange of the top channel section 15 and the various tongues or lugs 18 struck from the channel portion 15 as 35 clearly illustrated in Figure 3. It will, of course, be understood that the retaining ring 20 is only forced downwardly into the channel section 15 of the top member a distance sufficient to tightly stretch the skinhead over 40 the ridge or crown 17 formed by deflecting the beveled margin 16 of the top member. By constructing the top member with the inner peripheral beveled flange 16, the skinhead proper is supported on what might be 45 termed a knife edge rim so that a skinhead

of maximum diameter is provided for the instrument.

By providing the metal top ring 13 with the key hole slots 12 for receiving the lower ends of the instrument strings it will be noted that the use of the ordinary tail pieces is eliminated.

The top member is adapted to be stamped out of sheet metal and is so formed that it may be securely pressed into position by means of a mandrel press or other suitable instrument over the instrument casing side walls 2 with such a tight fit that it is practically impossible under ordinary conditions to remove the top from the instrument case or housing. The tight frictional fit of the flange 14 of the top member with the walls 2 of the instrument casing or housing eliminates the use of rivets or other means for securing the top in place.

Figures 5 to 8, inclusive, illustrate a modified form of musical instrument, in this case comprising a one piece sheet metal casing or body portion 24 having a closed bottom with depressions 25^a and 26 if desired. 50 Rigidly secured to the rim or side walls of the casing 24 is a neck portion 25 formed with a peg head 26 carrying pegs 27. Attached to the pegs 27 are the outer ends of strings 28 which are conducted over the neck portion 25 and over a bridge 29 with the lower ends of the strings engaged in key slots 30.

The key slots 30, as illustrated, are formed in spaced relation in a flat ring portion 31 forming a part of a top member. The ring portion 31 is provided with a plurality of spaced tone openings 32, thereby eliminating the use of F tone slots in the bottom of the casing or body section. Integrally formed on the outer edge or margin of the top ring member 31 is a rim or flange 33, which is adapted to be frictionally engaged on the upper end of the side walls of the casing 24. The top member also comprises a channel cross sectioned ring 34 which is integrally connected with the inner edge or margin of the top ring member 31 and said channel ring has struck therefrom a plurality of spaced tongues or lugs 35 with said lugs projecting into the channel ring member. Riveted to the bottom face of the channel ring member 34 between the tongues 35 are nuts 36. The upper margin of the inner flange of the top channel ring member 34 is bent downwardly and inwardly at an angle to form an inclined or beveled flange 37, thereby affording a bead or circular ridge at 38. A skinhead 39 is positioned over the bead 38 with the margin of said skinhead 125 projecting into the channel ring member 34 and having a plurality of radial slots therein to permit retaining screws 40 to be projected therethrough and engaged in the nuts 36. The screws 40 project through spaced 130

apertures in a stretching or retaining ring 41 which is over a channel cross section with the flanges of said retaining ring projecting downwardly into the channel ring 34 of the 5 top member. By tightening the screws 40, the inner peripheral flange of the retaining ring 41 engages the margin of the skinhead 39 and forces the same downwardly into the pockets afforded between the inner flange of 10 the top ring member 34 and the tongues 35 struck therefrom. With this arrangement it will be noted that the skinhead 39 is placed in position when dry and is stretched into place by means of the retaining ring 41 and 15 the screws 40. The skinhead is stretched in place without requiring previous wetting or forming on special fixtures as has been the practice heretofore.

While the improvements embracing the 20 present invention have been illustrated and described as being applied to a musical instrument such as a ukulele or a banjo attention is called to the fact that the improved top member and its retaining ring may be 25 used in connection with the construction of a snare drum or any other musical instrument requiring a stretched skinhead. In the case of equipping a snare drum or the like with the present invention both heads of the 30 drum may of course be formed in a similar manner, thereby permitting a drum of simplified construction to be furnished permitting each of the skinheads to be individually stretched or tightened in place, eliminating 35 the use of the present complicated mechanisms in use on drums of various kinds.

I am aware that many changes may be 40 made, and numerous details of construction may be varied through a wide range without departing from the principles of this invention, and I therefore do not purpose limiting the patent granted hereon, otherwise than necessitated by the prior art.

I claim as my invention:

45 1. In a stringed musical instrument of the class described the combination with a housing, of a grooved top member rigidly secured thereon, a beveled flange formed on the inner periphery of said top member affording an 50 annular ridge, tongues struck from said top member, nuts rigidly secured to said top member between said tongues, a skinhead positioned on said top member and resting on the annular ridge, a ring interfitting said 55 top member, and screws carried by said member and engaged in said nuts to force the ring member into the top member against the margin of the skinhead to force the margin of the skinhead into pockets formed by 60 said tongues to cause the skinhead to be stretched into position while dry over said annular ridge.

65 2. In a stringed musical instrument the combination with a housing, of a top member secured thereon having a plurality of

tongues struck therefrom, a beveled flange integral with said top member and forming an annular bead, nuts riveted to said top member between said tongues, a skinhead positioned over said annular bead, a channel 70 cross sectioned ring interfitting said top member and inclosing said tongues with one flange of the ring member projecting the margin of said skinhead into pockets formed by said tongues, and a plurality of screws 75 carried by said ring members and threaded through said nuts to be tightened to cause the ring members to stretch the skinhead while dry over said annular bead.

3. In a stringed musical instrument of the 80 class described the combination with a housing, of a pair of interfitting channel rings forming an end for said housing, tongues struck from one of said channel rings and projecting into the other of said channel rings, a beveled flange formed on the channel ring from which the tongues are struck with said beveled flange forming an annular bead, a skinhead positioned on said annular bead and having the margin thereof 85 projecting between said channel rings, and adjustable means for adjusting said channel rings with respect to one another to cause the skinhead to be stretched while dry over said annular bead with the margin of said 90 skinhead clamped between said channel rings and against said tongues.

4. In a stringed musical instrument the 95 combination with a stamped metal housing, of a stamped metal top member pressed thereon having a beveled flange integral therewith and tongues struck therefrom, nuts rigidly secured to said top members between said tongues, a skinhead supported by said top member above the beveled flange, a 100 ring engaging said skinhead and interfitting said top member, and screws carried by said ring and adjustably engaged in said nuts to be adjusted to cause the ring to stretch the skinhead while dry over the beveled flange 105 of said top member.

5. In a stringed musical instrument the 110 combination with a pressed metal housing, of a pressed metal grooved top member having a beveled flange and tongues integrally 115 formed thereon, nuts rigidly secured to the top member and projecting into said housing, a skinhead seated on said top member over the beveled flange, a channel cross sectioned ring interfitting with said grooved top member with one of the flanges of said ring engaging the margin of the skinhead to draw said margin over said tongues, and screws carried by said ring and engaged in 120 said nuts to be tightened to cause the skinhead to be tightly stretched in position while dry with the margin of said skinhead looping into pockets formed by said tongues and one of the walls of said top member.

6. A stringed musical instrument compris- 125

ing a body, a grooved channel ring secured thereon, a beveled flange integrally formed on said grooved channel ring and forming an annular ridge, nuts riveted to said channel ring, a plurality of tongues struck from said channel ring between said nuts, a skinhead seated on said annular ridge with the margin of said skinhead provided with spaced radial slots, a channel retaining ring interfitting said channel ring, and screws carried by said channel retaining ring pro-

jecting through the skinhead slots and engaged in said nuts to be adjusted to cause the retaining ring to stretch the skinhead while dry over said annular ridge with the 15 margin of the skinhead looped to project into pockets formed by said tongues and one of the walls of said channel ring.

In testimony whereof I have hereunto subscribed my name.

CLARENCE L. DEWEY.
